(57) **CLAIM**

The ornamental design for a battery charger, as shown and described.

DESCRIPTION

FIG. 1 is an front isometric view of a battery charger in accordance with the present invention.

FIG. 2 is a rear isometric view of the battery charger illustrated in FIG. 1A.

FIG. 3 is a front elevation view of the battery charger illustrated in FIG. 1A.

FIG. 4 is a left side elevation view of the battery charger illustrated in FIG. 1A.

FIG. 5 is a rear elevation view of the battery charger illustrated in FIG. 1A.

FIG. 6 is a top plan view of the battery charger illustrated in FIG. 1A; and,

FIG. 7 is a bottom plan view of the battery charger illustrated in FIG. 1A.

The broken lines shown in the drawings are included for the purpose of illustrating unclaimed portions of the battery charger and form no part of the claimed design.

1 Claim, 4 Drawing Sheets
